DESIGN FOR A COMBINED WALKER AND TRAY

Lewis W. Simms, Fairville, New Brunswick,
Canada

Application July 5, 1943, Serial No. 110,610

Term of patent 14 years

To all whom it may concern:

Be it known that I, Lewis W. Simms, a subject of the King of Great Britain, residing at the village of Fairville, in the county of St. John, in the Province of New Brunswick, Dominion of Canada, have invented a new, original, and ornamental Design for a Combined Walker and Tray, of which the following is a specification, reference being had to the accompanying drawing, forming part thereof.

Fig. 1 is a perspective view of the combined

walker and tray, showing my design, and illustrating the tray element in one position; and

Fig. 2 is a sectional view thereof, taken on a substantially vertical central plane, the tray element being illustrated in the reverse position.

Fig. 3 is a perspective view of the tray element.

I claim:

The ornamental design for a combined walker and tray, as shown and described.

LEWIS W. SIMMS.
